(57) **CLAIM**

The ornamental design for a portable coordinate measurement machine, as shown and described.

(**) Term: **14 Years**

(21) Appl. No.: **29/306,621**

DESCRIPTION

(22) Filed: **Apr. 11, 2008**

FIG. 1 is a perspective view of a portable coordinate measurement machine showing our new design in accordance with a third embodiment of the invention;

(51) **LOC (9) Cl. 10-04**

FIG. 2 is a side view of the portable coordinate measurement machine as shown in FIG. 1;

(52) **U.S. Cl. D10/63; D15/199**

FIG. 3 is a front view of the portable coordinate measurement machine as shown in FIG. 1;

(58) **Field of Classification Search D10/46,**

FIG. 4 is a rear view of the portable coordinate measurement machine as shown in FIG. 1;

D10/63; D15/199; 33/503-505, 558; 74/491.01-490.15;

FIG. 5 is a top view of the portable coordinate measurement machine as shown in FIG. 1; and,

319/560; 700/245, 262, 195, 80; 702/150-156,

FIG. 6 is a bottom view of the portable coordinate measurement machine as shown in FIG. 1.

702/94, 95, 167-169

A single side view is provided for the embodiment of the portable coordinate measurement machine as the opposite side is symmetric. Phantom lining, where utilized, is for illustrative purposes only and does not limit or form any part of the claimed design.

See application file for complete search history.
